(57) **CLAIM**

The ornamental design for pants, as shown and described.

DESCRIPTION

FIG. 1 is a perspective view of pants, showing my new design;

FIG. 2 is a front view thereof;

FIG. 3 is a left side view thereof;

FIG. 4 is a right side view thereof; and,

FIG. 5 is a top plan view thereof.

The broken lines shown in the drawings depict portions of the pants that form no part of the claimed design.
